(57) **CLAIM**

The ornamental design for the rotor blade for a toy helicopter, as shown and described.

DESCRIPTION

FIG. 1 is a perspective view of a rotor blade for a toy helicopter embodying my design;

FIG. 2 is a front elevational view thereof, the rear elevational and side elevational views being mirror images thereof;

FIG. 3 is a bottom plan view thereof; and,

FIG. 4 is a top plan view thereof.
